Application July 29, 1938, Serial No. 221,963

6 Claims.

(Cl. 103—5)

This invention relates to the well pumping art, and more particularly to an apparatus adapted to pump fluid from a well by the use of a fluid operated pump operating in combination with a gas lift device.

The invention is of particular utility in the oil industry, and, accordingly, will be described in connection with such use, although it is to be understood that the invention has other fields of use and that I do not intend to be limited by the particular use described.

It is common practice in the oil industry to inject gas under pressure into a column of oil in a well to cause the oil and gas mixture formed thereby to flow to the surface of the ground. Such "gas lifts," as they are termed in the industry, are of many well-known types, but in all of them gas under high pressure is injected into the column of oil to be raised, and in many of such gas lifts the gas pressure is directly communicated through the well oil to the producing formation. If, as is common, the well formation pressure causing the oil to flow into the well from the adjacent oil sands is low, the pressure exerted on the formation by gas of such a gas lift will materially decrease or entirely prevent the flow of oil from the formation into the well, and the gas lift will either be impractical or entirely inoperative to raise oil from the well. For example, it frequently occurs that the formation pressure in a well is in the neighborhood of 30 to 40 pounds per square inch, whereas it is common to use gas pressures in the gas lift of about 400 pounds per square inch in a deep well. In such cases, the high gas pressure communicated to the well formation opposes the formation pressure, and the gas lift is inoperative or impractical to raise oil from the well. In the use of all such gas lifts, therefore, the formation pressure determines the maximum gas pressure that can be employed in the lift, which is frequently much below the maximum gas pressure which would be used if this pressure did not oppose the flow of oil into the well. In other words, such gas lifts are incapable of producing the maximum possible flow of oil from the well and operate at low efficiency.

It is therefore a primary object of my invention to provide a gas lift device in which no gas pressure is applied to the well formation from the well opposing the formation pressure normally causing oil to flow into the well from the formation. I prefer to accomplish this by providing a packing means for forming a reservoir in the well, a pump for raising oil above the pack-

ing means into the reservoir, and a gas lift mechanism for injecting gas into the column of oil above the packing means to raise the oil from the well.

5 It is a further object of my invention to provide a gas lift device as described in the preceding paragraph which continuously raises oil from the well. Some types of gas lifts have been designed which operate intermittently, but I desire to avoid the low efficiency characteristic of such devices.

Another object of the invention is to provide a gas lift pumping device incorporating a displacement pump of the reciprocating piston type of low pressure and high volume to raise oil in a well to a point at which gas is injected into the oil to raise the oil to the surface of the ground, the pump operating at a pressure substantially equal to or slightly higher than the pressure of 15 the gas utilized, to prevent back pressure on the well formation. To accomplish this purpose I prefer to employ a fluid operated pump, although it will be understood that other types of such displacement pumps may be substituted therefor 20 without departing from the spirit of my invention.

Still another object of the invention is to provide a fluid operated pump adapted to operate at low pressure to pump continuously a high volume of fluid.

25 A further object of my invention is to provide a novel type of pumping mechanism for a well.

Another object of the invention is to provide a novel form of packing means for a well casing, 30 which includes means for hydraulically sealing the packing means in engagement with the casing.

35 A further object of the invention is to provide a novel type of pump piston having means for lubricating the surface thereof during operation.

Other objects and advantages will be apparent from the following description and drawings, in which:

40 Fig. 1 is a diagrammatic assembly view, partly in section, showing my invention disposed in a well.

45 Fig. 2 is a sectional view of the upper end of my invention.

50 Fig. 3 is a sectional view of the intermediate portion of my device, being continued downwardly from the lower end of Fig. 2.

Fig. 12 is a fragmentary sectional view taken on the line 12—12 of Fig. 11.

Referring to Fig. 1 of the drawings, I show an oil well 20 having the usual type of casing 21 therein secured at its upper end to a casing head 22, as is well known in the art. Secured at its upper end to the casing head 22 is a string of gas tubing 23 extending downwardly into the well and communicating through the casing head with a gas pipe 24 leading to a gas compressor 25 of any suitable type well known in the art. A gas inlet pipe 26 conducts gas from a suitable source (not shown) to the gas compressor 25. Extending downwardly within the gas tubing 23 is an operating fluid tubing 27 which passes upwardly through the casing head 22 and is suitably secured thereto, and leads to a high pressure delivery pump 28 adapted to receive suitable operating fluid from a source of supply (not shown) through an inlet pipe 29 and force it under high pressure downwardly through the tubing 27. The high pressure delivery pump 28 may be of any suitable design well known in the art.

As shown in Fig. 2, the lower end of the gas tubing 23 is threadedly connected by a collar 30 to a packing means 31 which is primarily designed to form a fluid-tight seal between the lower end of the gas tubing and the well casing 21. The packing means 31 is comprised of an upper outer tubular member 32 threaded at its upper end to the collar 30 and threaded at its lower end to a connector plug 33. The connector plug 33 has a threaded central bore 34 into which is threaded the lower end of an upper inner tubular member 35 which projects upwardly within the outer tubular member 32 and has secured to its upper end a guide element 36 having a flared bell-shaped mouth 37. The lower end of the operating fluid tubing 27 is connected through a collar 38 to a tubular fitting 39 having threaded in its lower end an externally tapered tip 40.

As will be described hereinafter, the flared mouth 37, the guide element 36, and the tapered tip 40 of the tubular fitting 39 cooperate to permit the tubular fitting to be inserted readily into the inner tubular member 35.

Secured to the lower end of the connector plug 33, as by threads or otherwise, is a cylindrical member 41 having a bore 42 in which a packer piston 43 makes a close sliding fit. The upper end of the packer piston 43 is provided with a packing cup 44, formed of leather or other resilient material, held by a follower cup 45 bolted to the packer piston by a bolt 46. The packing cup 44 prevents leakage of fluid between the packer piston 43 and the bore 42. The lower end of the packer piston 43 has secured thereto, as by a pin 47, a transverse arm 48 which extends through slots 49 in the cylindrical member 41 and has its

outer end rigidly connected to a packer sleeve 50.

The cylindrical member 41 has an intermediate wall 51 formed integrally therewith which closes the lower end of the bore 42 and forms a lower chamber 52 therein. Bridging the intermediate wall 51 are vertical passages 53 formed in the cylindrical member 41 which communicate between the lower chamber 52 and a space 54 formed between the upper end of the cylindrical member and the connector plug 33, as shown in Figs. 5 and 6. Externally threaded to the lower end of the cylindrical member 41 is a collar 55 which is in turn threaded to the upper end of an intermediate production tube 56, and internally threaded to the cylindrical member 41 is an inwardly flared collar 57 which is in turn threadedly connected to the upper end of an intermediate pressure pipe 58.

The intermediate production tube 56 is externally upset, as shown at 60 in Fig. 3, on which is secured a flange ring 61 on which rests a packer element 62 comprised of upper and lower clamp rings 63 and 64, respectively, between which is clamped a tubular packing 65 formed of rubber or other suitable material. The upper clamp ring 63 is adapted to slide on the intermediate production tube 56, and the upper end thereof is engaged by the lower end of the packer sleeve 50. Registering openings 66 and 67 are provided in the packer sleeve 50 and the intermediate production tube 56, respectively.

The lower end of the intermediate pressure pipe 58 is connected to a fluid operated motor 70 shown in detail in Figs. 9 and 10. Fluid operated motors are old in the art, and no claim is made herein to the specific construction shown in the fluid operated motor 70 hereof, the same being fully shown and described in my copending application, Serial No. 138,176, filed April 21, 1937, patented October 25, 1938, No. 2,134,174, to which reference is hereby made. It is to be understood that any suitable type of fluid operated motor may be substituted for the fluid operated motor 70 without departing from the spirit of my invention. In general, the fluid operated motor 70 includes a valve body 71 suitably attached to the upper end of a motor cylinder member 72, suitable passages 73 and 74 being formed therein to conduct operating fluid to opposite ends of the motor cylinder member. A master valve member 75 is provided in the valve body 71 to alternately open communication between the passages 73 and 74 and the intermediate pressure pipe 58, and pilot valve mechanism 76 is provided to cooperate with the upper end of an upper piston rod 77 to control the operation of the master valve member. The upper piston rod 77 extends downwardly into the motor cylinder member 72 and has connected to its lower end a motor piston 78 adapted to reciprocate in the motor cylinder member, the upper piston rod having a longitudinal passage 79 therethrough which is at all times in communication at its upper end with the intermediate pressure pipe 58.

Secured to the lower end of the intermediate production tube 56 is a pump mechanism 85, shown in detail in Figs. 3 and 4, which is adapted to pump well fluid from the lower end of the casing 21 upwardly to a point above the packing means 31. The pump mechanism 85 includes an upper inlet member 86 threadedly secured to the intermediate production tube 56 in which a plug member 87 of the fluid operated motor 70 is threaded. The upper inlet member 86 has

threaded thereto a pump cylinder member 88, to the lower end of which is threadedly secured a lower inlet member 89, as shown in Fig. 4. Threaded to the lower inlet member 89 is a lower tubular element 90 having its lower end closed by a suitable plug 91.

The upper inlet member 86 is provided with upper inlet passages 92 which communicate between the exterior of the upper inlet member and a pump bore 93 of the pump cylinder member 88, which passages provide means for ingress of well fluid into the upper end of the bore 93. Also formed in the upper inlet member 86 are vertical passages 94 which provide open communication between the upper end of the pump bore 93 and the lower end of the intermediate production tube 56. Check valve means 96 are provided at the upper end of the pump bore 93 to control the inlet and discharge of well fluid into and out of the upper end of the pump bore. The check valve means 96 is comprised of a valve seat member 97 which rests on a cylinder liner 98 provided in the pump cylinder member 88, the valve seat member having an external diameter smaller than the internal diameter of the pump cylinder member so as to provide an annular space 99 therebetween, and having discharge passages 100 formed therein which communicate between the upper end of the pump bore 93 and the space 94a. An annular discharge valve element 101 is provided to move vertically on a tubular extension 102 formed on the upper inlet member 86 and is normally held by a spring 103 so as to close the discharge passages 100. These elements form an upper discharge check valve which permits fluid to discharge from the pump bore 93 through the space 94a and the vertical passages 94 into the intermediate production tube 56, but prevent a reverse flow of fluid. The valve seat member 97 is also provided with inlet passages 104 which communicate between the upper inlet passages 92 of the upper inlet member 86 and the pump bore 93. Threaded into the tubular extension 102 of the upper inlet member 86 is a plug element 104a which assists in clamping the valve seat member 97 to the upper inlet member, and on which is positioned an annular inlet valve member 105 which is normally held by a compression spring 106 in engagement with the valve seat member 97 so as to close the inlet passages 104, to prevent fluid from passing from the upper end of the pump bore 93 outwardly through the upper inlet passages 92, but permitting the reverse flow of fluid from the well.

Threadedly connected to the lower end of the motor piston 78 is an intermediate piston rod 110 having a longitudinal passage 111 therethrough, suitable packing 112 being provided between the intermediate piston rod and the plug member 87 to prevent leakage of fluid therebetween. The intermediate piston rod 110 is extended downwardly through a suitable bore in the upper inlet member 86 and through the plug element 104a, and is threaded at its lower end to a pump piston 113, as shown in Fig. 4. The pump piston 113 may be of any suitable type, but I prefer to construct this pump piston with a central body 115 having a bore 116 and having formed thereon an annular flange 117 against which are positioned upper and lower packing cups 118 and 119, respectively, which hold upper and lower packings 120 and 121, respectively, made of rubber or other resilient material, the same being held in position by upper

and lower follower cups 122 and 123, respectively, which are threaded on the central body 115. The packings 120 and 121 prevent leakage of fluid past the pump piston 113.

5 The lower inlet member 89 is threadedly secured to the pump cylinder member 88 and is formed to control the flow of well fluid into and out of the lower end of the pump bore 93 below the piston 113, being generally similar in construction and function to the upper inlet member 86. The lower inlet member 89 is provided with lower inlet passages 125 which communicate between the pump bore 93 and the exterior of the lower inlet member, the upper ends thereof being closed by an inlet check valve member 126, similar in construction to the annular inlet valve member 105, and adapted to permit well fluid to flow through the lower inlet passages into the pump bore but constructed so as to prevent a reverse flow thereof. A lower valve seat member 127 is also provided, being in all respects similar to the valve seat member 97 and being provided with lower discharge passages 128 closed by a lower discharge valve element 129 similar to the discharge valve element 101, to permit fluid to flow from the pump bore 93 through the passages 128 into a lower annular space 130 communicating directly with the lower end of liner passages 131 formed in the cylinder liner 98.

10 Threadedly secured in the bore 116 of the pump piston 113 is a lower piston rod 132 which extends downwardly through the lower inlet member 89, having suitable packing 133 therebetween to prevent leakage, and extends into a lower tubular member 134 threadedly secured to the lower inlet member and having its lower end closed. The lower piston rod 132 is provided with an axial passage 135 which passes from end to end thereof and communicates with the central bore 116 of the pump piston 113.

15 When installing my device in a well, the parts thereof are assembled substantially as shown in Figs. 2, 3, and 4, at which time the transverse arm 48 of the packing means 31 is in its uppermost position, and the device is lowered into position in the well 20 suspended from the lower end of the gas tubing 23. The operating fluid tubing 27 may or may not be run into the well in assembled position, and it will generally be found preferable to lower the gas tubing 23 to working position before the operating fluid tubing is lowered into the well. The flared bell-shaped mouth 37 formed on the guide element 36 is specifically provided so as to guide the externally tapered tip 40 of the tubular fitting 39 secured to the lower end of the operating fluid tubing 27 into the position shown in Fig. 2. When the device and its parts are in the positions shown, the high pressure delivery pump 28 is actuated to receive pressure fluid, such as oil, from a suitable source of supply (not shown) through the inlet pipe 29 and to convey it under high pressure through the operating fluid tubing 27 downwardly therethrough to the fluid operated motor 70. As soon as fluid pressure in the operating fluid tubing 27 is exerted on the packer piston 43 and its parts, this pressure causes the packer piston to move downwardly in the bore 42, thus moving downwardly the transverse arm 48 and the packer sleeve 50 connected thereto. Since the lower end of the packer sleeve 50 engages the upper clamp ring 63 of the packer element 62, downward movement of the sleeve presses the tubular packing 65 between the upper and lower clamp rings 63 and 64, causing the

tubular packing to be compressed and expanded outwardly into sealing engagement with the well casing 21, as shown in Fig. 1. It will thus be observed that a fluid-tight seal is formed between the packing means 31 and the well casing 21 at all times that operating fluid under high pressure is in the operating fluid tubing 27, and it is an important feature of my invention to provide such a packing means which is hydraulically actuated. It will be understood that as soon as pressure is released on the column of pressure fluid in the operating fluid tubing 27, the natural resiliency of the tubular packing 65 will operate to force the upper clamp ring 63 and the packer sleeve 50 in engagement therewith upwardly so as to permit withdrawal of the packing means 31 from the well casing 21.

High pressure operating fluid fills the space 54 and freely flows therefrom downwardly through the vertical passages 53 into the lower chamber 52 of the cylindrical member 41, from whence it passes through the inwardly flared collar 57 into the intermediate pressure pipe 58, passing therefrom through a screen strainer member 140 directly into the upper end of the fluid operated motor 70. As indicated above, the fluid operated motor 70 is of a type well known in the art, the high pressure fluid flowing alternatively through the passages 73 and 74, as controlled by the position of the master valve member 75, into the upper and lower ends of the motor cylinder 72a, to reciprocate the motor piston 78 therein. Reciprocation of the motor piston 78 reciprocates the upper piston rod 77 to actuate the pilot valve mechanism 76 controlling the operation of the master valve 75, and reciprocates the intermediate piston rod 110 which has connected at its lower end the pump piston 113. It is to be noted that the high pressure fluid from the intermediate pressure pipe 58 has direct access at all times through the longitudinal passage 79 of the upper piston rod, the motor piston 78, the longitudinal passage 111 of the intermediate piston rod 110, the bore 116 of the pump piston 113, and the axial passage 135 of the lower piston rod 132 to a space 141 at the bottom of the lower tubular member 134. It will thus be understood that the pressure on the upper and lower ends of the piston rods are balanced, which feature is fully covered in my Patent No. 2,081,220, issued May 25, 1937, and that high pressure fluid is free to flow through the piston rod at all times.

Reciprocation of the pump piston 113 causes it to pump fluid from the well casing 21. When the pump piston 113 is raised from the position shown in Fig. 4, any fluid thereabove will discharge through the discharge passages 100 of the valve seat member 97 into the space 94a from which it is forced upwardly through the vertical passages 94 into the lower end of the intermediate production tube 56 and thence upwardly therethrough. As the pump piston 113 rises in the pump bore 93, a suction is created below the pump piston which opens the lower inlet check valve member 126 against the action of its spring to draw fluid into the lower end of the pump bore from the well casing 21 through the lower inlet passages 125.

When the pump piston 113 moves downwardly in the pump bore 93, upon reversal of its stroke, the lower inlet check valve member 126 closes in response to pressure thereon, and the lower discharge valve element 129 opens to permit fluid to flow from the lower end of the pump bore 93

into the lower annular space 130, and thence upwardly through the liner passages 131 into the space 94a where it mixes with the oil discharged from the upper end of the pump cylinder, and flows therefrom upwardly through the vertical passages 94 into the intermediate production tube 56. Downward movement of the pump piston 113 permits the discharge valve element 101 to close in response to the action of the spring 103, and suction is set up in the upper end of the pump bore 93 which opens the inlet valve member 105 to draw well fluid into the upper end of the pump bore through the upper inlet passages 92 and the inlet passages 104 of the upper valve seat member 97. Thus, continued reciprocation of the pump piston 113 provides a steady flow of well fluid discharging from alternate ends of the pump bore, and causes the same to rise upwardly through the intermediate production tube 56 from whence it passes outwardly through the registering openings 67 and 68 into a reservoir space 142 formed by the packer element 62 and the well casing 21, the well fluid flowing upwardly therefrom directly through the well casing to a point above the collar 30. Those skilled in the art will understand, from the present disclosure, that although I prefer to use the fluid operated motor 70, or a similar type of motor, to actuate the pump mechanism 85, I do not intend to be limited to the use of such a fluid operated motor for this purpose, and that any other suitable means may be employed to reciprocate the pump piston 113, such as, for example, sucker rods which are well known in the art, without departing from my invention.

A suitable gas or other fluid, such as air, is drawn from a suitable source of supply through the gas inlet pipe 26 by the gas compressor 25, in which the gas is compressed to a suitable operating pressure and conducted through the gas pipe 24 and the casing head 22 to the gas tubing 23, in which it passes downwardly therethrough to the collar 30, passing outwardly therefrom through the gas discharge openings 30a to mix with the column of well fluid confined therabove in the reservoir space 142 of the packing means 31.

As is well known in the art, such gas forms bubbles in the column of well fluid confined in the reservoir space 142, which reduce the average specific gravity of the well fluid and gas mixture thus formed to a sufficient degree to cause the mixture to flow upwardly through the casing 21 to the surface of the ground, where it discharges through the discharge pipe 26a.

It will therefore be understood that the gas pressure employed in lifting the well fluid through the casing is not applied directly to the well formation, but is merely imposed on the column of well fluid in the reservoir space 142, and that the pressure under which the fluid operated pump mechanism 85 delivers well fluid to the reservoir space 142 need only be sufficient to offset the gas pressure employed. Thus, for example, if a gas pressure of 400 pounds per square inch is required to lift the column of well fluid from the reservoir space 142 to the discharge pipe 26a, the pump mechanism 85 may be designed and operated to pump a high volume of well fluid at a pressure of only approximately 400 pounds per square inch, or slightly higher, from the well into the reservoir space 142. It will also be understood that whereas fluid operated pumps heretofore employed in deep well pumping have been designed to pump a low vol-

ume of well fluid at a high pressure, my present fluid operated pump is designed to pump a high volume at low pressure, a function impossible in prior pumps of the fluid operated type.

In Figs. 11 and 12, I show an alternative form of pump piston 150 which it may be desirable to use in place of the pump piston 113 shown in Fig. 4. The pump piston 150 has a cylindrical body 151, adapted to make a sliding fit in the pump bore 93 of the cylinder liner 98, the exterior thereof being provided with annular channels 152 receiving piston rings 153 as is well known in the art. The cylindrical body 151 has an upper central bore 154 threadedly receiving the lower end of the intermediate piston rod 110, and has a lower central bore 155 threadedly receiving the upper end of the lower piston rod 132, the ends of the rods being spaced apart by a chamber 156. Offset from the axis of the cylindrical body 151 is a valve cylinder 157 which is closed at its lower end by a lower plug 158 and has at its upper end an upper plug 159 provided with a passage 160 therethrough. Slidably disposed in the valve cylinder 157 is a regulator valve member 161 having a cup-shaped piston 162 within which a compression spring 163 is disposed so as to engage both the piston and the upper plug 159, and the valve member is provided with a transverse opening 164 which registers with a port 165 communicating between the interior of the valve cylinder 157 and the exterior of the cylindrical body 151. The cylindrical body 151 is provided with a transverse opening 166 into which is threaded a transverse pin 167 having a vertical fluid passage 168 communicating with a longitudinal fluid passage 169, one end of the transverse pin projecting into the transverse opening 164 of the valve member 161 and having threaded thereon a tubular cap 170 having a valve orifice 171 therein. Secured to the valve member 161 and projecting upwardly in the transverse opening 164 is a conical valve element 172 adapted to seat in the lower end of the valve orifice 171 to close it, the valve member being provided with a passage 173.

My piston 150 is designed to permit a flow of operating fluid under relatively high pressure to the sliding surfaces of the piston and the liner 98 to lubricate them and to prevent foreign materials from lodging therebetween, which is broadly covered in my Patent No. 2,081,220, issued May 25, 1937, the present construction being an improvement thereon. In a deep well installation, such as, for example, a well 6500 feet deep, the pressure of the operating fluid may be as high as 4000 pounds per square inch, whereas in using my present pump the fluid load on the pump piston 150 may only be 400 pounds per square inch. Obviously, if operating fluid under a high pressure, such as 4000 pounds per square inch, is conveyed to the outer surface of the piston, it will either cause excessive leakage lengthwise of the piston or will require an excessive functional duty to be imposed on the piston rings 153. Consequently, the principal object of my piston design shown in Figs. 11 and 12 is to provide a pressure reducing means for reducing the pressure of the operating fluid to a value approximating the fluid load on the pump piston 150.

In operation, operating fluid under pressure is at all times in the longitudinal passage 111 of the intermediate piston rod 110 and in the axial passage 135 of the lower piston rod 132, communication therebetween being afforded through the

chamber 156 of the pump piston 150. The operating fluid flows through the vertical and longitudinal fluid passages 168 and 169, through the tubular cap 170, and through the orifice 171 into the transverse opening 164. The spring 163 normally exerts a downward force on the valve member 161 tending to hold it in open position in which the valve element 172 is out of seating engagement with the valve orifice 171. Operating fluid then passes through the passage 173 into the lower end of the valve cylinder 157, and exerts an upward force on the valve member 161 tending to move the valve member upwardly against the action of the spring 163, and any fluid pressure in the valve cylinder 157 in excess of that required to balance the spring 163 causes the valve member 161 to move upwardly tending to close the valve element 172 in the orifice 171. The spring 163 is selected to balance a counter fluid force slightly greater than the maximum fluid load on the piston 150. For example, if the maximum fluid pumping load on the piston 150 is approximately 400 pounds per square inch, the spring 163 is set to resist movement of the valve member 161 until the pressure of the operating fluid rises above a predetermined maximum, such as 500 pounds per square inch. Thus, if the normal pressure on the operating fluid is 4000 pounds per square inch, the excess pressure in the valve cylinder 157 below the valve member will move the valve member 161 upwardly until the valve element 172 is sufficiently closed so that the spring 163 will balance the pressure of the fluid in the valve cylinder. It will thus be understood that this construction operates as a regulator to maintain the pressure of operating fluid flowing outwardly through the transverse opening 164 and the port 165 below a predetermined maximum, thus preventing excessive leakage of operating fluid lengthwise of the piston 150, and permitting the use of relatively light frictional contact of the piston rings 153 with the bore 93 of the liner 98. It will also be understood that this piston construction may be used to advantage in other devices, and I do not intend to be limited to its use in connection with a fluid operated pump.

Although I have herein shown and described a simple and practical embodiment of my invention, I do not intend to be limited to the details of construction disclosed but intend my invention to be accorded the full scope of the following claims.

I claim as my invention:

1. In a deep well pumping device, the combination of: a high-volume low-pressure fluid operated pump in the lower part of a well; operating fluid tubing extending downwardly in said well and communicating with said pump; production tubing extending downwardly through said well and communicating with said pump; gas tubing extending downwardly through said well and having a port at its lower end communicating with said production tubing at a point adjacent said pump; means for supplying operating fluid through said operating fluid tubing to said pump to actuate said pump to pump a relatively high volume of well fluid at a relatively low pressure from said well into said production tubing to a level above said port; and means for supplying gas under pressure through said gas tubing and said port into said well fluid in said production tubing to raise said well fluid through said production tubing to the upper end thereof.
2. In a device for use in connection with a

fluid operated deep well pump having a supply tubing for supplying the pump with operating fluid and a production tubing for conveying the well fluid discharged by said pump to the surface of the ground, the combination of: packing means adapted to form a fluid-tight seal between the pump and the production tubing; a piston having one face thereof in communication with the operating fluid in said supply tubing, said operating fluid being at all times in open communication with said pump through said supply tubing; and means connecting said piston to said packing means so that movement of said piston in response to fluid pressure of said operating fluid expands said packing means to form said seal.

3. In a deep well pumping device, the combination of: a production tubing extending downwardly in a well; a fluid operated pump in the lower part of the well and adapted to pump fluid from said well into said production tubing; a gas tubing extending downwardly within said production tubing and having a port at its lower end communicating with said production tubing at a point adjacent said pump; an operating fluid tubing extending downwardly within said gas tubing and communicating with said pump; means for supplying operating fluid through said operating fluid tubing to said pump to actuate said pump to pump fluid from said well into said production tubing; and means for supplying gas under pressure through said gas tubing and said port into said well fluid in said production tubing to raise said well fluid through said production tubing to the upper end thereof.

4. In a deep well pumping device, the combination of: a production tubing extending downwardly in a well; a fluid operated pump in the lower part of the well and adapted to pump well fluid from said well into the lower end of said production tubing, said pump including a motor cylinder therein, a pump cylinder of substantially greater diameter than said motor cylinder having a pump piston therein, piston rod means connecting said pistons, and fluid means for reciprocating said motor piston to reciprocate said pump piston so as to cause said pump to discharge a relatively high volume of well fluid into said production tubing at a pressure insufficient to raise said well fluid through said production tubing to the upper end thereof; a gas tubing extending downwardly within said production tubing and

having a port at its lower end communicating with said production tubing at a point adjacent said pump; an operating fluid tubing extending downwardly within said gas tubing and communicating with said pump; means for supplying operating fluid through said operating fluid tubing to said pump to actuate said pump to pump fluid from said well into said production tubing; and means for supplying gas under pressure through said gas tubing and said port into said well fluid in said production tubing to raise said well fluid through said production tubing to the upper end thereof.

5. In a deep well pumping device, the combination of: a production tubing in a well; a fluid operated pump in the well and adapted to discharge well fluid into the lower end of the production tubing; an operating fluid tubing extending downwardly within said production tubing and at all times in open communication with said pump to supply the same with operating fluid under relatively high pressure; packing means adapted to form a fluid-tight seal between said pump and said production tubing; a piston having one face thereof in communication with said operating fluid in said operating fluid tubing; and means connecting said piston to said packing means so that movement of said piston in response to fluid pressure of said operating fluid expands said packing means to form said seal.

6. In a deep well pumping device, the combination of: a production tubing in a well; a fluid operated pump in the well and adapted to discharge well fluid into the lower end of the production tubing; an operating fluid tubing extending downwardly within said production tubing and at all times in open communication with said pump to supply the same with operating fluid under relatively high pressure; packing means adapted to form a fluid-tight seal between said pump and said production tubing; a piston having one face thereof in communication with said operating fluid in said operating fluid tubing; and means connecting said piston to said packing means so that movement of said piston in response to fluid pressure of said operating fluid expands said packing means to form said seal, the release of fluid pressure on said operating fluid permitting said packing means to contract to break said seal.

CLARENCE J. COBERLY.
